(57) **CLAIM**

The ornamental design for a solar spotlight, as shown and described.

DESCRIPTION

FIG. 1 is a top view of a solar spotlight of the present invention.

FIG. 2 is a bottom view of the solar spotlight shown in FIG. 1.

FIG. 3 is a left view of the solar spotlight shown in FIG. 1.

FIG. 4 is a right view of the solar spotlight shown in FIG. 1.

FIG. 5 is a front view of the solar spotlight shown in FIG. 1; and,

FIG. 6 is a back view of the solar spotlight shown in FIG. 1.

The broken line disclosure represents portions of the solar spotlight which form no part of the claimed design.
